UNITED STATES PATENT OFFICE.

GASTON A. BRONDER, OF BROOKLYN, NEW YORK, ASSIGNOR OF ONE-HALF TO THOMAS COSTIGAN, OF NEW YORK, N. Y.; LUCIA R. BRONDER ADMINISTRATRIX OF SAID GASTON A. BRONDER, DECEASED.

VAPOR EXTRACTOR.

Application filed June 11, 1921. Serial No. 476,800.

To all whom it may concern:

Be it known that I, GASTON A. BRONDER, citizen of the United States, and resident of the borough of Brooklyn, city of New York, in the county of Kings and State of New York, have invented certain new and useful Improvements in a Vapor Extractor, of which the following is a specification.

10 This invention relates to a vapor extractor and is an improvement of the extractor shown and described in my United States Letters Patent No. 1,361,005 for the vapor extractor bearing date December 7th, 1920. 15 Its object is the production of a vapor extractor by means of which the volatile substances of shale, fuel coal, lignite and the like is extracted.

The organization of the invention comprises essentially a generating chamber and a preheating hopper with their appurtenances. The generating chamber is fed from the preheating hopper. The heat of gas or liquid fuel is used to heat the charge in the generating chamber and the products of combustion of said gas or liquid fuel is used in the preheating hopper.

In the accompanying drawings Fig. 1 represents a vertical section of an exemplification of the extractor as on line 1, 1, of Fig. 2 with portions thereof in full lines; Fig. 2 shows a right hand side view of Fig. 1; Fig. 2^a shows a section of Fig. 2 on the line 2^a, 2^a; Fig. 3 indicates a section of Fig. 1 on the line 3, 3; Fig. 4 represents a section of Fig. 1 on the line 4, 4; Fig. 5 shows a section of Fig. 1 on the line 5, 5; Fig. 6 indicates a section of Fig. 1 on the line 6, 6; Fig. 7 is a section of Fig. 1 on the line 7, 7; Fig. 8 shows an enlarged vertical section of some details; Fig. 9 is an enlarged section of Fig. 8 on the line 9, 9; Fig. 10 shows an enlarged section of Fig. 5 on the line 10, 10 and Fig. 11 indicates a section of Fig. 3 on the line 11, 11.

The extractor comprises a generating chamber 15 with the cylindrical shell 16, having the top or roof 17 with the openings 18 and 19 and the bottom 23 with the opening 24. A hopper bottom shaped outlet 25 is fastened to the lower face of the bottom

23 and registers with the opening 24. Lugs 30 and 31 extend from the wall of the outlet 25. In the lug 30 is located a pin 32, and a supporting bar 33 has one end pivoted on the pin 32, while at the other end of the bar is formed a slot 34. A swing bolt 35 with a nut has one end pivoted to the lug 31 while its other end extends through the slot 34. An adjusting screw 36 is in threaded engagement with an opening in the bar 33. An operating wheel 37 is fastened to one end of the screw, while a disc shaped head 38 is formed with the other end of the screw 36. A swinging lower door 42 has formed therewith the hinge sleeve 43 which is pivoted on the pin 32. A cavity is formed in the door 42 for the head 38 and a plate 44 is fastened to the lower face of the door to maintain the head 38 in operative position.

A tower for the vapor extractor comprises the four columns 54, with the bottom cross beams 55, 56, upon which are supported the longitudinal bottom beams 57 and 58. Top cross beams 59 are fastened adjacent to the upper ends of the columns 54 and longitudinal beams 60 extend between the upper portions of said columns. Longitudinal beams 61 are supported on the top cross beams 59. Ties 62 are supported on the beams 61 for the tracks 63.

A charging mouth piece and vapor outlet opening is fastened to the roof 17 over the opening 18 thereof. The mouth piece 66 that comprises the cylindrical portion 66 that has extending therefrom the outlet nozzle 67. A lug 68 similar to the lug 30 and a lug 69 similar to the lug 31 are formed with said portion 66. An upper door 70 similar to the door 42 is provided for the said portion 66 and a bar 71 with the operating wheel 72, similar respectively to 33 and 37 are provided for the door 70. Vapor outlet piping 76 extends from the roof 17 over the opening 19 in said roof 17. An opening 78 is formed in the wall 16. A door casting 79 with the door 80 is fastened to the shell 16 over said opening 78. An opening 83 is formed at the lower portion of the shell 16. A U shaped shell 84 has its ends fastened throughout

the whole length to the shell 16 forming thereby a heating chamber 85. The lower end of the shell 84 is supported on the bottom 23 and is fastened thereto by means 5 of the angle iron 86. The shell 84 extends up to the roof 17 and at its upper end has formed therein an opening 87. An inlet conduit 88 is fastened to the upper end of U shaped shell 84 over the opening 10 87. A fan casing 89 with the fan wheel 90 is fastened to the inlet end of the conduit 88. A journal bearing 91 extends from the bottom wall of the casing 89. A bracket 94 extends from the lower wall 15 of the fan casing 89 and has journaled therein one end of the armature shaft 95 of an electric motor 96. The armature shaft is also journaled in the bearing 91. A connecting suction conduit 97 extends 20 from a central opening of the fan casing 89 to the outlet nozzle 67.

In the conduit 97 is journaled an indicating propeller 100. The said propeller is fastened to a shaft 101, which latter is 25 journaled in the sleeve 102. The sleeve 102 has formed therewith a flange 103 that bears upon and is fastened to the roof of the suction conduit 97. A small indicator disc 104 is fastened to the shaft 101.

30 In the heating chamber 85 are located a cluster or a plurality of heating tubes indicated each in their entirety by the letter A and in Fig. 1 are shown diagrammatically. Each of the heating tubes comprises 35 an upper slideable nipple 110 threaded only at its lower end. A cast iron pipe 111 with the radiating ribs 112 is interiorly threaded at its upper end, for the lower end of the nipple 110, to which latter it is connected. The pipe 111 is also interiorly threaded at its lower end for the short connecting nipple 113, to which latter it is connected. A second cast iron pipe 116, similar to 111, is in threaded engagement 40 at its upper end with said nipple 113. A nipple 117 is in threaded engagement with the lower end of the pipe 116 at one end and with the bottom 23 of the shell 16 at the other end.

50 The upper nipple 110 slidably extends through the roof 17. A stuffing box 120 is fastened to said roof 17 axially in line with said nipple 110 and is provided with the screw gland 121 for the packing 122.

55 A spiral guide strip 123 is located in each tube A, and is held in place by means of a hook 124 which has one end extending into an opening in the top end of the nipple 110 and its other end is bent over the top edge of said nipple. A plurality of gas pipes 125 have extending therefrom the gas outlet tips 126. Each of the latter is located axially under one of the heating tubes A. It is to be understood that the 60 heating tubes A may be modified by in-

creasing the number of cast iron pipes with their connections.

A pair of longitudinal I beams 130 have their opposite ends fastened to the inner face of the shell 16. A pair of similar rolling grates are indicated in their entireties by the letters B and C. Each of said grates comprises the grate bars 132, which at one end are supported upon and fastened to the cross beam 133. At the end of each of the 70 beams 133 are fastened journal pins 134, and on the latter are journaled rollers 135. The rollers 135 are in rolling contact with the flanges of the I beams 130. The outer end of each grate has connected thereto the 75 front cross beam 136. Eyelets 137 extend from each of the beams 136. A valve casting is indicated in its entirety by the letter D and comprises the outer cylindrical valve seat 140, the flange 141 and the connecting 80 portion 142. A port 143 is formed in the casing D and extends throughout its whole length and inside width. A cylindrical valve 145 with a central port 146 is seated in the valve seat 140. The valve 145 has 85 formed at its ends the shanks 147 with the operating openings 148. The outer ends of each grate B and C extends through an opening 149 in the shell 16.

A pair of brackets 155 are connected to 90 the columns 54, and each support an hydraulic cylinder 156, with the piston rod 157 and the piston 158. A four-way valve cock is shown with the casing 160 having the inlet and outlet ports 161, 162, the inlet port 163 and the waste port 164. Piping 165 and 166 respectively connect the ports 162 and 161 with the ends of the cylinder 156. An inlet pipe 167 is connected to the inlet port 163 in the usual way. A plug valve 168 with the usual ports 169 and 170 is seated in the casing 160. An extension 171 is formed with plug valve 168 and has extending therefrom the operating handle 172.

A pair of chains 173 extend from each piston rod 157. Inclined stationary grates 174 are supported at their lower ends upon the beams 130 and their upper ends bear against the wall of the shell 16.

A triangular and tapered releasing bar 175 is located in the shell 16 and has formed at its upper end a cylindrical projection 176. A sleeve 177 is supported and fastened to the roof 17 to guide the said cylindrical portion 176. The lower end of the bar 175 is normally supported upon one of the grates in the shell 16.

A waste gas outlet nozzle 180 is fastened to the roof 17 over the whole cluster of tubes A and has in turn supported thereon the guide sleeve 181. A fan casing 182 has formed therewith at its lower end the suction inlet sleeve 183 and at its upper portion is formed the journal bearing 183^a. The sleeve 183 is rotatively supported in the 180

guide sleeve 181. A fan wheel 184 is located in the casing 182. A bracket 185 is supported on the cover of the fan casing 182 and has journaled therein the upper end of the 5 armature shaft 186 of the electric motor 187. The lower end of the shaft 186 is journaled in the bearing 183^a. The said armature shaft extends through the roof of the casing 182 and has fastened thereto the fan wheel 10 184. A nozzle 188 has one end fastened to the casing 182. A hopper shaped funnel 189 is fastened to the strap 190 the ends of which latter are fastened to the fan casing 182 and to the nozzle 188. A funnel shaped preheating hopper 192 has 15 formed therewith the nozzle 193 which is detachably fastened to the nozzle 188.

Angle irons 195 are fastened to the beams 60 and in turn are fastened to the wall of 20 the hopper 192. In the lower end of the hopper 192 is located a grate 198, which has extending therefrom a rack bar 199. From the nozzle 193 of the hopper 192 extend a pair of arms 200, which at their outer ends 25 are connected by a cross brace 201. The latter has formed therein a guide opening 202. Journal bearings 203 extend up from the cross brace 201 and have journaled therein the shaft 204. A pinion 205 is fastened to 30 the shaft 204 and meshes with the rack bar 199. An operating wheel 206 is fastened to one end of the shaft 204. A brick lining 210 encircles the shells 16 and 84.

To operate the vapor extractor, shale, 35 canel coal or similar materials are deposited into the funnel shaped preheating hopper 192, the grate 198 of which has been previously moved to its closed position. At this time the nozzle 188 has been located to one 40 side of the outlet nozzle 193, and thereby any small particles of shale or other material that may have passed between the bars of the grate 198 are separated from the charge in the hopper 192 and disposed of. Next the 45 upper door 70 of the generating chamber 15 is fully opened. The operator now swings the funnel 189 in line with and under the outlet nozzle 193 and also in line with and over the opening 18 in the roof 17 of the generating chamber 15. The grate 198 is now 50 moved to its open position and the charge from the preheating hopper 192 is deposited into the generating chamber 15, the grates B and C being in their closed position, but the 55 lower door 42 is open to allow the escape of any small particles of material that may escape between the bars of the grates B, C, and 174. After the grates B and C are located in their closed position the valves 145 60 are turned to close the ports 143 in the valve casings D.

The door 42 is next tightly closed. The funnel 189 is now swung from and out of line with the outlet nozzle 193, to locate the 65 nozzle 188 in line with said nozzle 193. The

nozzle 188 is now fastened to the nozzle 193. The upper door 70 is next closed and the grate 198 is moved to its closed position and another charge of material is placed in the preheating hopper 192. Both the fan 70 wheels 90 and 184 are started, by means of their respective motors and a circulation of cold air is first established through the charge in the generating chamber 15 and in the hopper 192. Cold air is drawn by 75 means of the fan wheel 90 from the generating chamber 15 through the cylindrical portion 66 of the mouth piece, the outlet nozzle 67, thence to the fan casing 89, and from the latter it is forced through the inlet conduit 88 and then into the heating chamber 85. The air next flows downwardly between the heating tubes A, through the opening 83 into the shell 16 at the lower end of the generating chamber 15. The air next flows 85 through the openings in the grates B, C and 174, and thence through the charge in the generating chamber.

The gas of the burners is next turned on 90 and the gas mixture flowing from the Bunsen gas outlet tips 126 is lit. The fan wheel 90 continues to draw the air, which is now being heated, from the generating chamber 15 and forces it into the inlet conduit 88 and from thence into the heating chamber 85 on the outside of the heating tubes A and by virtue of which the air is heated each time that it flows through the chamber 85. The heated air flows from the chamber 100 95 105 110 115 120 125 130 135 140 145 150 155 160 165 170 175 180 185 190 195 200 205 210 215 220 225 230 235 240 245 250 255 260 265 270 275 280 285 290 295 located in the generating chamber 15, has previously been preheated in the hopper 192, thereby utilizing the products of combustion of the burners of the extractor.

5 To empty the generating chamber 15 the gas supply is first cut off and both the fan wheels 90 and 184 are stopped. Then the lower door 42 is swung open, and the grates B and C are opened by means of the hydraulic cylinders 156, and the connecting chains 173 which latter are connected to the eyelets 137, the cylindrical valve 145 having been turned to locate the port 146 in register with the port 143. The releasing bar 175 is next forced down and its lower end drops to the bottom 23 of the generating chamber 15, releasing said bar from the charge therein. The charge within generating chamber 15 being hot and expanded will 10 be released and drop from said generating chamber 15 by virtue of the gap left therein when displacing the bar 175. Next the lower door 42 is swung to its closed position and fastened in place. The triangular 15 releasing bar 175 is now held in place in its upper position and the grates B and C are moved to their closed position by the hydraulic cylinder 156 and the bar 175 is supported on the grate C. The upper door 70 20 is next fully opened and the nozzle 188 is detached from the outlet nozzle 193 and swung aside to bring the funnel 189 under the outlet nozzle 193. Next the upper grate 198 is opened and the preheated charge in 25 the hopper 192 drops into the generating chamber 15. The upper grate 198 is moved to its closed position, and the upper door 70 is closed and tightened in place. A new 30 charge of material is now dumped into the hopper 192, and after the small particles of 35 the charge drop through the grate 198 and the funnel 189, the nozzle 188 is fastened to the nozzle 193, and the operations are continued. The fan wheels are preferably 40 stopped when the charge from the hopper 45 192 is dumped into the chamber 15 and also when discharged from the latter. The circulation through the connecting suction conduit 97 and its rapidity is indicated by 50 means of the small indicating disc 104 of the shaft 101 that carries the indicating propeller 100.

Having described my invention what I desire to secure by Letters Patent and claim 55 is:—

1. In a vapor extractor the combination of a generating chamber for a material to be operated upon, a preheating hopper to feed said material to said chamber, heating means 60 to circulate heated air through the material in said chamber, the heat of the air being imparted to the material in the chamber and generating therefrom gases and vapor that circulate with the circulating air and means 65 to conduct the products of combustion from

said heating means to and through the material in said preheating hopper to preheat the charge of material therein.

2. In a vapor extractor the combination of a generating chamber for a material to be operated upon, a preheating hopper to preheat said material before entering the generating chamber, a heating chamber adjacent to the generating chamber, heating tubes extending through the heating chamber, 70 burners for the heating tubes to transmit heated air through the tubes, means to twirl the air when flowing through the tubes, means to lead said heated air with the products of combustion from the burners through the charge of material in said hopper, the generating chamber and heating chamber connecting one with the other at one end thereof and means at the other end of the heating chamber to circulate the heated air therein on the outside of the tubes with the gases and vapors generating in the generating chamber in a closed cycle through the material in the generating chamber and through the heating chamber on the outside 80 of its heating tubes.

3. In a vapor extractor the combination of a shell with an opening at its lower end and forming a generating chamber, a roof with openings and a bottom with an opening for said shell, a second shell fastened to the outer face of the first shell constituting a heating chamber and its interior in connection with the interior of the generating chamber by means of said lower opening in the latter, means to circulate and heat air in said heating chamber and force it therefrom through the generating chamber and then again through the heating chamber, means to charge a material into the generating chamber, means to discharge said material from the generating chamber and means to discharge gases and vapors from the generating chamber when above atmospheric pressure. 90 100 105

4. In a vapor extractor the combination of a shell with an opening at its lower end and forming a generating chamber, a roof with openings and a bottom with an opening for said shell, a second shell fastened to the outer face of the first shell constituting a heating chamber and its interior in connection with the interior of the generating chamber by means of said lower opening in the latter, tubes extending through the heating chamber, a mouth-piece with one end thereof connected to the roof of the generating chamber, in register with one of the openings therein, connecting means between said mouth-piece and the upper portion of the heating chamber, a rotating fan-wheel in said means, means to circulate heated air through the tubes in the heating chamber, a detachable door for the mouth-piece, adjustable grates in the generating chamber, 115 120 125 130

an outlet connected to the bottom of the generating chamber in register with the opening therein, a door detachably connected to the outlet and vapor outlet piping extending from the roof of the generating chamber and in register with the other opening therein.

5. In a vapor extractor the combination of a shell with an opening at its lower end 10 and forming a generating chamber, a roof with openings and a bottom with an opening for said shell, a second shell fastened to the outer face of the first shell between its roof and bottom constituting a heating 15 chamber and its interior in connection with the interior of the generating chamber by means of said lower opening in the latter, tubes extending through the heating chamber, a mouth-piece with one end thereof 20 connected to the roof of the generating chamber in register with one of the openings therein, a connecting suction conduit with one end connected to a nozzle extending from the mouth-piece, a fan casing with 25 a fan-wheel connected to the other end of said suction conduit, an inlet conduit connecting the fan casing with the upper end of the heating chamber, means to circulate heating air through the tubes in the heating 30 chamber, a detachable door for the roof of said mouth-piece, movable grates in the generating chamber, an outlet connected to the bottom of the generating chamber in register with the opening therein, and vapor outlet piping extending from the roof 35 of the generating chamber and in register with the other opening therein.

6. In a vapor extractor the combination of a shell forming a generating chamber 40 for a material to be operated upon, a charging mouth-piece for the chamber, a pair of valve casings each having a port therethrough attached to opposite sides of the shell in register with openings therein, a 45 rotative valve having a port seated in each valve casing, means to rotate each valve to locate its port in register with the port of the valve casing, a pair of movable grates in the generating chamber adapted to ex-

tend through the ports of the valve and 50 valve casing and an outlet for the generating chamber.

7. In a vapor extractor the combination of a generating chamber, means to charge the chamber with a material to be operated 55 upon, a pair of valve casings each having a port therethrough attached to the wall of the chamber in register with openings therein, a valve with a port for each valve casing, means to locate each valve with its 60 port in register with the port of its valve casing, a pair of movable grates in the chamber each adapted to extend through the port of one of the valves and the port of its casing and a fluid moved piston and 65 piston rod for each grate adapted to move it through the ports of its adjacent valve casing and valve.

8. In a vapor extractor the combination of a generating chamber, a grate in the 70 chamber and a tapering releasing bar in the chamber with the large end thereof normally supported on the grate and its other end extending through the roof of the chamber.

9. In a vapor extractor the combination of a generating chamber, a heating chamber for the generating chamber, tubes extending through the heating chamber, burners with their products of combustion rising up 80 through the said tubes, a preheating hopper and means to draw into the latter the products of combustion of said burners.

10. In a vapor extractor the combination of a generating chamber, a heating chamber adjacent to the generating chamber, a plurality of heating tubes extending through the heating chamber, burners with their gas tips under each tube, a preheating hopper over the generating chamber, detachable connections between preheating hopper and the heating chamber and a rotating fan wheel in said connections.

Signed at the borough of Manhattan, city 95 of New York, in the county of New York and State of New York, this 3rd day of June, A. D. 1921.

GASTON A. BRONDER.
